UNITED STATES PATENT OFFICE.

GEORGE I. WICKS, OF CLEVELAND, OHIO, ASSIGNOR, BY DIRECT AND MESNE ASSIGNMENTS, TO ELLIOTT-FISHER COMPANY, OF NEW YORK, N. Y., A CORPORATION OF DELAWARE.

ADDING-ATTACHMENT FOR TYPE-WRITERS.

No. 838,068.

Specification of Letters Patent.

Patented Dec. 11, 1906.

Application filed August 4, 1902. Serial No. 118,280.

To all whom it may concern:

Be it known that I, GEORGE I. WICKS, a citizen of the United States, residing at Cleveland, in the county of Cuyahoga and State of Ohio, have invented a certain new and useful Improvement in Adding Attachments for Type-Writers, of which the following is a full, clear, and exact description, reference being had to the accompanying drawings.

10 The object of this invention is to produce a simple and efficient adding mechanism adapted for use in combination with a type-writer, particularly a flat-platen or book type-writer, so that as numbers are written in column by 15 the type-writer the column-total will be computed and registered by the adding mechanism.

Other objects subordinate to that stated will hereinafter appear as the description of 20 the preferred embodiment of the invention is developed.

In the accompanying drawings, Figure 1 is a plan view of a portion of the traveling carriage of a Fisher book type-writer equipped 25 with my adding mechanism. Fig. 2 is a sectional end elevation of the same. Fig. 3 is a vertical section on the line 3 3 of Fig. 2 designed particularly to show the driving-gears for the master-wheel. Fig. 4 is a trans- 30 verse sectional view of the computing device and its supporting means. Fig. 5 is a sec- tional elevation of the computing device on the line 5 5 of Fig. 4. Fig. 6 is a detail sec- tional elevation on the line 6 6 of Fig. 5, 35 showing the relation of a number-wheel and its transfer-dog; and Fig. 7 is a front eleva- tion of a Fisher type-writer equipped with my adding mechanism.

A designates the carriage of a book type- 40 writer, which carriage travels laterally or in the direction of letter-spacing on the machine-frame 1, which travels longitudinally of the subjacent flat platen 2 to line-space the writing. The carriage A supports the printing mechanism, which includes the keys a, their stems a', the key-levers a², fulcrumed on sup- 45 ports a³, and the draw-wires a⁴, connected at their lower ends with the downwardly- swinging type-bars a⁵. The depression of a 50 key of the type-writer causes a character—as, for instance, a digit—to be printed on the work-sheet supported by the platen, and the

release of the key causes an escapement (not shown) to release the carriage, which then advances the distance of a letter-space, as 55 usual.

In accordance with my invention the computing device proper is mounted on the frame 1 of the machine, while the operating mechanism for said device is mounted on 60 the carriage and is movable therewith, so that as the movement of the carriage advances the printing mechanism to successive denominational positions or orders of the column of numbers on the work-sheet the operating mechanism will be similarly advanced to corresponding denominational members 65 of the computing device.

Secured to the rear of the carriage A are a pair of supports B and B', in which are 70 mounted one above the other a pair of parallel shafts C and C', the former of which may be termed the "actuator-shaft." Rotatable on the shaft C is a gear-wheel D, to which is attached a ratchet-wheel d, engaged by a 75 pawl e', carried by an arm e, mounted to swing from said shaft. The arm e is connected by a link e² with an oscillatory driving member including an operating-arm e³, extended rearwardly from a hollow shaft e⁴, 80 journaled on a rod e⁵, carried by supports e⁶, rising from the carriage A. Extended forwardly from the shaft e⁴ are nine tubular shanks e⁷, in which are secured adjustable arms e⁸, pivotally connected to the upper 85 ends of nine vertically-disposed links e⁹, the lower ends of which are extended through the top of the carriage-casing and carry rollers e¹⁰, disposed in the paths of the num- 90 eral-key levers a² in rear of the fulcrums a³ thereof. The links e⁹ are guided by links e¹¹, which swing from suitable supports e¹², mounted on the plate e¹³, secured to the top of the carriage. When a numeral-key is de- 95 pressed, the corresponding link e⁹ is elevated by the key-lever, and through the inter- mediate connections the pawl e' is drawn down to rotate the ratchet-wheel d and the connected gear-wheel D a distance deter- 100 mined by the distance between the roller e¹⁰, carried by said link, and the fulcrum a³ of the key-lever. The distance between the ful- crums of the key-levers and the lower ends of the links e⁹ vary in accordance with the

various values of the digits represented by the numeral-keys. Thus the depression of the "1" key will cause the ratchet-wheel d to be advanced a single increment or unit of movement—as, for instance, the distance of one tooth—while the depression of the "9" key will cause an advance of nine increments or teeth, the motion transmitted from the intermediate numeral-keys being similarly proportionate to their respective values.

The wheel D , which is fixed to the ratchet d , as stated, is geared to a pinion d' , rotatable on the upper shaft C' and fixed to a gear-wheel d'' , which meshes with a pinion d'' , keyed or otherwise secured to the lower shaft C , Fig. 3. Through the medium of this gearing a driving connection is established between the ratchet d and a master actuator-wheel, or pinion c , fixed on the extended right-hand end of the actuator-shaft C . The master wheel or pinion c has ten peripheral teeth, and the ratio of the described gearing is such that for each unit of advance of the wheel d the pinion c is turned the distance of one of its teeth.

The computing device proper is inclosed in a casing F , supported by a bracket F' , located at the rear of the type-writer and adjustably secured to the main frame 1 thereof. The bracket F' preferably rests upon a plate F'' , extending between the carriage-guides G and G' , and is secured by a bolt F''' , passed through the bracket and plate and screwed into a clamp member F''' , bearing against the under sides of the plate F'' and the ribbon-feed rack g , fixed to the rear guide G' .

The casing F consists of two end plates f and f' and an intermediate wall f'' and is formed to produce two tubular chambers f'' and f''' , the denominational members or number-wheels H , located in the latter, being observable through a sight-opening f'''' . While the number of denominational members or wheels is immaterial, I have shown an aligned series of eight wheels H , which will accommodate a total ranging from cents to millions of dollars. Exhibited on the periphery of each number-wheel are the digits "0" to "9" inclusive, equidistantly spaced and presentable in succession before the sight-opening f'''' as the wheel is rotated. Each number-wheel has also a central opening of sufficient size to receive the master-pinion c and is formed with ten internal teeth h , adapted to mesh with those of the pinion. When the printing-point of the type-writer is located at the left of the column to be totalized, the master-pinion c will be out of engagement with the computing device, so that the latter will not be operated when numbers are printed outside of the column selected by the adjustment of the computing device on the frame of the type-writer. When, however, the movement of the carriage A to the left presents the printing-point of the ma-

chine opposite the highest order of the column, the master-pinion c will be presented in mesh with the highest member or wheel of the computing device. If, now, a numeral-key is depressed, a digit will be printed in the millions order of the column, and the millions-wheel of the computing device will be rotated a number of increments or units of movement corresponding to the value of the printed digit. When the key is permitted to rise, the carriage will advance in the usual manner to the next lower order or denomination of the column, and the master pinion or actuator will likewise advance to the next lower number-wheel, the denominational relation of the pinion with respect to the computing device corresponding at all times to the denominational relation of the printing mechanism with respect to the column on the work-sheet.

When the value accumulated upon a given wheel reaches the limit of that particular denomination, it is necessary to transfer such value to the wheel of next higher denomination. To attain this end, I have devised a simple and efficient transfer or carrying mechanism, which when any given wheel moves from "9" to "0" will automatically advance the wheel of next higher denomination a single increment or step—as, for instance, from "0" to "1." Mounted on a rod j , extending across the chamber f'' of the casing F , is a series of swinging gear-carriers J , urged forwardly by springs j' and having noses j'' , which bear upon the peripheries of the number-wheels H . These gear-carriers serve to hold the wheels against accidental rotary movement and also as carriers for transfer wheels or gears K , each gear-carrier, except the one opposite the number-wheel of highest order, being provided on its left-hand side with a boss j''' , upon which one of said transfer or carrying wheels K is mounted. The wheels H and K are peripherally toothed, and each transfer-wheel K when moved forward by its gear-carrier is adapted to mesh with two number-wheels H , so that as the one of lower order is moved from "0" to "9" the transfer-wheel will transmit such motion to the one of higher order.

Normally the transfer-wheels are held back in inoperative position by the gear-carriers; but each number-wheel H is provided with a notch h'' , so disposed in its periphery that when said wheel is moved to the "9" position the nose j'' of its gear-carrier will drop into the notch, and thus cause the wheel carried by the gear-carrier to move into engagement with the wheel so moved and the one to the left thereof. (See Figs. 4, 5, and 6.) Therefore when the wheel previously moved to "9" is moved to "0" the value accumulated thereon will be transferred to the wheel of next higher order in an obvious manner. After the carrying is accomplished

the movement of the wheel engaged by the gear-carrier will cause the nose of the latter to ride out of the notch, thus restoring the transfer-wheel to its normal inoperative position, where it will remain until the notch again arrives opposite the nose of the gear-carrier.

To provide for resetting the number-wheels to zero upon the completion of a given computation, I provide a resetting member in the form of a pinion l , similar to the master-pinion c , but normally locked in an inoperative position beyond the right-hand end of the series of number-wheels. The pinion l is fixed at the inner end of a resetting shaft or rod L , having a knurled head l' at its outer end and journaled in a boss f' , extended from the right-hand side of the computing-device casing F . Interposed between the end of the boss f' and the knurled head l' is a spring l'' , which insures the retention of the resetting-wheel l in its inoperative position, but permits the shaft l to be moved endwise for the purpose of placing the resetting-wheel in mesh with successive number-wheels. In order to reset the computing device, it is simply necessary to first move the resetting-shaft L endwise to present the wheel in mesh with a number-wheel, after which the shaft may be rotated to reset the wheel. The successive number-wheels are reset in the manner described. When the resetting operation is completed, the shaft l is released and is returned to its normal position by the spring l'' .

What I claim is—

1. In a type-writer, the combination with a frame, a traveling carriage, and printing mechanism mounted on the carriage and including numeral-keys, of a computing device adjustable on the frame according to the location of the column to be printed and added and including a series of hollow denominational members and carrying means, a master-actuator movable with the carriage and arranged to enter and operate successive denominational members of the computing device, and mechanism intermediate of the master-actuator and the numeral-keys whereby the operative movement of the master-actuator will correspond in degree with the value of the particular numeral-key depressed.

2. The combination with a type-writer including a frame, a laterally-movable carriage, and printing mechanism mounted on the carriage and including numeral-keys, of a computing device laterally adjustable upon the frame of the type-writer and including a series of denominational members having internal gears, a shaft movable by the carriage, a master-wheel fixed upon one extremity of the shaft and movable into mesh with successive internal gears of the computing device, a rocking member mounted on the type-

writer carriage and operatively related to the several numeral-keys, and an operating connection between the rocking member and the shaft, said connection including pawl-and-ratchet mechanism arranged to cause the intermittent rotation of the master-wheel in one direction.

3. The combination with a computing device including a series of denominational members, of an actuator-shaft, a master-wheel secured at one end of the shaft and adapted to engage successive denominational members of the computing device, a ratchet-wheel loosely mounted on the shaft, a train of gearing between said ratchet-wheel and the shaft, a pawl engaging the ratchet-wheel, and keys for operating the pawl.

4. The combination with a computing device including a series of denominational members, of an actuator-shaft, a master-wheel mounted on said shaft and arranged to engage successive denominational members of the computing device, a ratchet-wheel loosely mounted on the actuator-shaft, a pawl for operating the ratchet-wheel, keys connected to the pawl, a second shaft geared to the actuator-shaft, and gearing between the ratchet-wheel and the second shaft.

5. The combination with a computing device including a series of denominational members, of an actuator-shaft, an actuator carried thereby and arranged to engage the several denominational members of the computing device in succession, a rocking member, a series of keys each arranged to cause the rocking member to be moved a different distance, a ratchet-wheel loosely mounted on the actuator-shaft, a pawl engaging the ratchet and having connection with the rocking member, and a train of speed-gearing between the ratchet-wheel and the actuator-shaft.

6. The combination with a computing device including a series of denominational members having internal gears, an actuator-shaft, a master-wheel secured to one end of said shaft and arranged to engage successive gears of the computing device, a rocking member, a series of keys each arranged to cause said member to be rocked at a different distance, and an operating connection between the rocking member and the actuator-shaft, said connection including pawl-and-ratchet mechanism and a train of speed-gearing.

7. The combination with a computing device including a series of denominational members, a master-wheel arranged to engage successive members, a rocking member, means whereby the rocking member will rotate the master-wheel in one direction only, a series of arms extended from the rocking member, a series of key-levers, keys connected to the levers, and a series of pendent

links each connected to one of the arms of the rocking member and having its lower end disposed in the path of a key-lever.

8. The combination with a computing device including a series of denominational members, of operating mechanism for the computing device including a rocking member, a series of arms extended therefrom, links connected to said arms, a series of numeral-key levers, links pivotally connected to the arms and engaging the key-levers at different distances from the fulcrums thereof, and keys connected to the key-levers.

9. In combination with a type-writer including a frame, a carriage and printing mechanism, said printing mechanism including type-bars, key-levers and keys, of a computing device including a series of denominational members, a master-wheel arranged to engage successive members, a rocking member, an operating connection between the rocking member and the master-wheel, a series of arms extended from the rocking member, and a series of links pendent from the arms and disposed to engage the key-levers at different distances from the fulcrums thereof.

10. The combination with a computing device including a series of denominational members, of operating means for said members including an operating member having a series of arms, links connected to said arms, levers engaging the links to move the operating member, and guide-links pivotally connected to the links first named.

11. The combination with a computing device, of operating mechanism therefor including a series of keys and key-levers, a series of links, a roller carried by each link and engaging a key-lever, an operative connection between the links and the computing device, and a series of guide-links each pivotally connected to one of the links first named.

12. The combination with a type-writer including a frame, a carriage, and printing mechanism mounted on the carriage and including numeral-keys and numeral-key levers, of a computing device and operating mechanism therefor including a rocking member mounted on the carriage, a series of pendent links connected to the rocking member and having their lower ends disposed in the paths of the key-levers, and a series of guide-links each pivoted to the type-writer carriage and to one of the links first named.

13. The combination with a computing device including a series of wheels occupying different denominational positions, an inclosing wall constituting the sole support and bearing for said wheels, a master means for operating the several wheels in succession, and carrying mechanism.

14. The combination with a computing device including a series of wheels occupying

different denominational positions and having internal gears, of an inclosing wall constituting the sole support and bearing for the several wheels, a master-pinion arranged to engage and operate each of the several internal gears in succession, and carrying mechanism for the wheels.

15. The combination with a computing device including a series of hollow wheels, carrying mechanism therefor, and a casing comprising two chambers one inclosing the carrying mechanism and the other being of substantially cylindrical form and forming an external bearing for the several wheels, of a master-actuator arranged to enter and operate the several wheels in succession.

16. The combination with a casing having a partially-cylindrical chamber and a second chamber communicating therewith, of a series of number-wheels located in the first-named chamber and guided by the wall thereof, each of said number-wheels being provided with an internal gear, means within the second chamber for gearing any number-wheel to the next adjacent wheel, and a pinion movable to engage the several internal gears in succession.

17. In a computing device, the combination with a series of denominational members, of a series of movable carriers each having its position controlled by a denominational member, a series of carrying devices normally supported in inoperative positions by the carriers and each movable with a carrier to effect an operative connection between two denominational members.

18. In a computing device, the combination with a series of number-wheels, of a series of movable gear-carriers having their positions controlled thereby, and a series of carrying-gears mounted on the gear-carriers and each movable with a carrier to engage two adjacent number-wheels.

19. In a computing device, the combination with a series of number-wheels, of a series of movable gear-carriers each engaging a number-wheel and serving to prevent accidental movement thereof, and a carrying-gear mounted on each of the gear-carriers and movable therewith to engage a pair of number-wheels.

20. The combination with a series of notched number-wheels, of a series of gear-carriers each retained in one position by a number-wheel but movable to another position when the notch in said number-wheel arrives opposite the carrier, and carrying-gears mounted on the gear-carriers and movable therewith to engage the number-wheels.

21. In a computing mechanism, the combination with a series of number-wheels having both internal and external teeth, of a master-actuator arranged to engage the internal teeth of successive number-wheels, and a series of carrying-gears each arranged to en-

gage the external teeth of a pair of number-wheels.

22. In a computing mechanism, the combination with a plurality of number-wheels each having both internal and external teeth and a notch, of means engaging the internal teeth of the number-wheels to operate the same, a series of gear-carriers, and a series of carrying-gears each mounted on a gear-carrier and movable therewith to engage a pair of number-wheels when the notch of one number-wheel comes opposite the carrier which supports the carrying-gear.

23. The combination with a series of denominational members having internal gears, of a master-pinion and a resetting-gear normally located beyond opposite ends of the series of denominational members and each movable laterally to engage the internal

gears of successive denominational members.

24. In a computing mechanism, the combination with a series of denominational members and carrying means each of said members having internal gears, of a master-pinion, means for moving said pinion to engage the internal gears of successive denominational

members, keys for rotating the pinion to operate the members engaged, and a resetting-gear movable laterally to engage the internal gears of successive denominational members and rotatable to reset said members to their normal positions.

25. The combination with a number-wheel and a gear-carrier, one having a notch and the other a projection, a carrying-gear mounted on the gear-carrier and movable therewith to engage the number-wheel when the movement of said wheel brings the notch and projection in apposition and thus permits the gear-carrier to move toward the wheel, and a second number-wheel which is also engaged by the carrying-gear when the latter is moved into engagement with the number-wheel first named, whereby movement may be imparted from one number-wheel to the other through the medium of the gear.

In testimony whereof I hereunto affix my signature in the presence of two witnesses.

GEORGE I. WICKS.
